Primary Examiner—Nelson C. Holtje*Assistant Examiner*—Antoine D. Davis**[57]****CLAIM**

The ornamental design for the pyrometer position guide for griddles, as shown and described.

DESCRIPTION

FIG. 1 is a perspective view of a pyrometer position guide for griddles showing my new design;

FIG. 2 is a top plan view;

FIG. 3 is a bottom plan view;

FIG. 4 is a front elevational view;

FIG. 5 is a rear elevational view; and,

FIG. 6 is a left side elevational view thereof, the right side elevational view being identical.

FIG. 1 has been drawn on a reduced scale with respect to FIGS. 2-6 while the broken line disclosure of a human being operating an instrument and a griddle are for environmental purposes only and form no part of the claimed design.
